CLAIM

The ornamental design for a self-service payment terminal, as shown and described.

DESCRIPTION

FIG. 1 is a top, front, right side perspective view of a self-service payment terminal showing our new design; FIG. 2 is a top, rear, left side perspective view thereof; FIG. 3 is a bottom, rear, left side perspective view thereof; FIG. 4 is a front elevation view thereof; FIG. 5 is a rear side elevation view thereof; FIG. 6 is a left side elevation view thereof; FIG. 7 is a right side elevation view thereof; FIG. 8 is a top plan view thereof; FIG. 9 is a bottom plan view thereof; and, FIG. 10 is another perspective view thereof shown in an alternate state for vertical mount use.

(Continued)

The broken lines in the drawings depict portions of the self-service payment terminal that form no part of the claimed design.

1 Claim, 10 Drawing Sheets
